York, N. Y., a corporation of New York

Application January 4, 1939, Serial No. 249,182

18 Claims. (Cl. 124—11)

This invention relates to toys, and more particularly to a repeating pellet shooting toy, preferably simulating a gun, and preferably shooting corks.

The primary object of our invention is to generally improve toys of this character.

Toy pop guns are very old. More recently, such guns have been improved for repeated operation by keeping the cork captive within the muzzle of the gun and using the cork repeatedly for successive noise-producing operations. However, with such a gun the cork is not discharged from the gun, and there is no simulation of actual flight of a projectile. The toy merely produces a noise.

In accordance with features and objects of the present invention, we provide a toy having a cork magazine which is preliminarily loaded with a series of corks. These may be fired successively from the gun. The toy is realistic because it not only produces a noise, but also expels a simulated projectile. However, there is no danger of injury because the projectile, when made of cork, as is preferably the case, is extremely light in weight and resilient.

The cork is preferably expelled by means of air compressed in a cylinder in front of a spring-actuated piston. The cork is not carried directly in the end of the cylinder, but instead is carried in one of a series of chambers in the cork magazine, said chamber being disposed in communication with the cylinder and acting as a continuation thereof. It would be difficult or impossible to maintain a tight fit between the magazine and cylinder, for the magazine is movable past the end of the cylinder. A snug engagement would make it difficult to feed the magazine. One object of the present invention is to overcome the foregoing difficulty and with this object in view, the magazine is made readily movable—in fact, it is even spaced somewhat from the end of the cylinder. Auxiliary sealing mechanism is provided for pulling the magazine tightly against the end of the cylinder when the gun is being fired. The operation of the sealing means is only intermittent, and the magazine is released for free movement when it is being advanced to bring another cork in front of the air compressing cylinder.

To the accomplishment of the foregoing and other more specific objects which will hereinafter appear, our invention consists in the air compressing and cork-carrying elements, and their relation one to the other, as hereinafter are more particularly described in the specification and

sought to be defined in the claims. The specification is accompanied by drawings in which:

Fig. 1 is a perspective view showing a toy embodying features of the present invention, and simulating a sub-machine gun;

Fig. 2 is a section taken in elevation through the cork shooting magazine of the gun shown in Fig. 1;

Fig. 3 is a similar view but showing the relation of the parts at the end of the firing stroke;

Fig. 4 is a transverse section taken in the plane of the line 4—4 of Fig. 3;

Fig. 5 is a perspective view showing the application of the invention to a gun simulating an automatic pistol;

Fig. 6 is a section taken in elevation through the cork shooting mechanism of the gun shown in Fig. 5;

Fig. 7 is a similar view showing the relation of the parts at the end of the firing stroke;

Fig. 8 is a horizontal view taken on the line 8—8 of Fig. 6, and explanatory of the feed mechanism for the cork magazine;

Fig. 9 is a section taken in elevation through another toy simulating an automatic pistol, but provided with a different type of operating mechanism;

Fig. 10 is a horizontal section taken in the plane of the line 10—10 of Fig. 9;

Fig. 11 is an end elevation of the gun shown in Figs. 9 and 10;

Fig. 12 is a fragmentary view similar to Fig. 9, but showing the relation of the parts at the end of the firing stroke of the gun;

Fig. 13 is a section taken in the plane of the line 13—13 of Fig. 9, and is explanatory of the feed mechanism for the cork magazine;

Fig. 14 is a side elevation of a toy simulating a revolver, the cork magazine being located at the simulated cylinder or cartridge magazine of the revolver;

Fig. 15 shows the gun of Fig. 14 with one side of the body removed to expose the internal mechanism;

Fig. 16 is explanatory of a detail, and is taken on the line 16 of Fig. 15;

Fig. 17 is a perspective view of the muzzle portion of a simulated sub-machine gun utilizing a flexible cork magazine;

Fig. 18 is explanatory of the construction of the magazine;

Fig. 19 is a perspective view illustrating a straight cork magazine;

Fig. 20 is a section showing the construction of the same; and

Fig. 21 is a schematic diagram explanatory of the method of using the same.

Referring to the drawings, and more particularly to Fig. 1, the toy there shown simulates a sub-machine gun, and comprises a simulated barrel 12, a stock 14, a forward grip 16, a rearward grip 18 which acts also as a trigger, or firing lever, and a cork magazine 20. The magazine 20 is provided with a series of individual cork chambers 22. These are preliminarily loaded with pellets acting as projectiles. The pellets are preferably ordinary corks of the frustoconical type used for corking bottles. Such a cork is shown being discharged from the muzzle of the gun, at 24. It will be observed that the forward portion 26 of the barrel is very much larger in diameter than the cork 24, and the movement of the cork is in no way impeded by the barrel. In fact, its flight is a free flight directly from the cork chamber of magazine 20, and the forward portion 26 of the barrel is added merely to improve the appearance of the toy and to more closely simulate a gun. The cork is expelled by mechanism carried in a frame 28, the upper part of which is housed in barrel 12, and the lower part of which is housed in a body portion 30 beneath the gun barrel.

The internal mechanism carried by frame 28 and including the trigger 18 and cork magazine 20, may be bodily removed from the gun. This mechanism is shown in Figs. 2, 3, and 4, and is next described.

The cork is expelled by compressed air. The air is compressed in a metal cylinder 32 the forward end of which is curled inwardly at 34 and receives a rubber gasket 36. A piston 38 is reciprocable in cylinder 32. It is mounted at the forward end of a piston rod 40 formed out of a flat strip of metal. Piston rod 40 is surrounded by a powerful compression spring 42 the forward end of which bears against piston 38, and the rear end of which bears against a suitable reaction plate 44 secured between the side plates 46 of the frame.

Operating lever or trigger 18 is pivotally mounted at 48. The trigger is a flattened tubular member the forward and rear sides 50 of which are cut away at the upper portion. It carries a pawl 52 pivotally mounted thereon at 54. The pawl is normally urged upwardly by a spring 56. The forward end or hook 58 of the pawl engages in a slot 60 cut through piston rod 40. It will be evident that as trigger 18 is drawn rearwardly from the position shown in Fig. 2 to that shown in Fig. 3, the piston rod 40 will be pulled rearwardly by pawl 52 from the position of Fig. 2 to the broken line position 40' of Fig. 3. At this time, however, the upper camming portion 62 of the pawl rides against the lower edge of plate 64, and the latter forces the pawl downwardly, thereby disengaging the hook 58 from the piston rod. The spring 42 is thus released and abruptly forces the piston 38 to forward position.

The cork magazine is in the present case a rotatable or wheel-like magazine, and it may be conveniently made by die-casting methods. It comprises a hub 66 (Fig. 3) at the center of a generally circular plate 68 carrying a series of peripherally disposed cork chambers 70. These may be cylindrical as shown, and are suitably dimensioned to tightly receive the corks, insertion of the corks preferably being arrested by the tapered shape thereof before the inner ends reach the back of the cork chamber. A hole 72 is cut through the magazine at the rear of each

chamber for communication between the air compressing cylinder 32 and the cork chamber. The magazine is rotatably mounted on a shaft 74 carried in transverse walls 76 and 78 of the frame. It will be evident from inspection of Fig. 3 that the shaft 74 is so located as to bring the top-most cork chamber directly in alignment with the cylinder 32. In fact, the cork chamber forms a continuation of the air cylinder, and the arrangement is much the same as though the topmost cork had been inserted directly in the end of the air cylinder.

One important difference, of course, is the possibility of leakage of air between the cylinder and the cork chamber. This is particularly true in view of the provision of a substantial clearance between the cork magazine and gasket 36, as is clearly shown in Fig. 2. This difficulty is overcome in the present case by the provision of special sealing means for clamping the cork chamber against gasket 36 at the time that the cork is discharged. The sealing mechanism comprises a rod or strip 80 overlying the frame 28 and connected at its rear end to the trigger 18. Specifically, strip 80 is provided with side-wardly projecting ears 82 which are received in holes cut through the side walls of trigger 18. The forward end of strip 80 carries a depending stud 84. The periphery of the cork magazine carries a ledge or rim 86. This may be a continuous rim, or, if desired, and in order to conserve metal, it may be discontinuous, as is best shown in Fig. 4. It will be evident on comparison of Figs. 2 and 3 that as the trigger or operating lever 18 is pulled rearwardly, the strip 80 is drawn rearwardly, thus causing the stud 84 to bear against the ledge or rim 86 of the cork magazine, thereby pulling the magazine and particularly the local cork chamber tightly against the rubber gasket 36. This condition is, of course, maintained during the discharge of the gun, for the piston is released, as shown in Fig. 3, while the trigger is still held in rearward position.

Between successive operations of the trigger 18, the cork magazine is rotated or advanced to bring another cork into position for discharge. In the present case, this is done by feed mechanism comprising a pawl 88 pivoted at 90 and having an arm 92 connected to the forward end of a link 94. The rear end of link 94 is pivotally connected to trigger 18 at 96. The pivot 90 is preferably in the form of an eyelet which is slidably received in a slot 98. A spring wire 100 has a part passing through eyelet 90, and another part bearing against the frame wall 78, this spring being coiled at 101 and functioning to normally urge the pawl to the forward position shown in solid lines in Fig. 3.

The rear surface of the center portion 68 of the cork magazine is provided with a ring of cup-like recesses or indentations 102. These correspond to the cork chambers, and in the present case, there are twelve cork chambers and 12 recesses 102. In its rest position, the trigger 18 is forward and the pawl 88 is in the position shown in Fig. 2. When the trigger is drawn rearwardly, the pawl is turned from the position shown in Fig. 2 to that shown in Fig. 3. During this movement, the pawl moves from a lower one of the recesses 102 to the next higher recess. The necessary rearward movement of the pawl to pass from one recess to the next is accommodated by the slot 98. In other words, during its movement from the position of Fig. 2 to the solid line position of Fig. 3,

the pawl intermediately assumes the broken line position of Fig. 3. It will be evident that as trigger 114 moves forwardly from the position of Fig. 3 to the rest position of Fig. 2, the pawl 142 will advance the cork magazine one step, thus bringing a new cork into firing position.

In order to insure accurate registration of the cork with the air cylinder, the gun may be provided with pilot means or spring detent means. Specifically, we provide a horizontally reciprocable rod 104, said rod being normally urged forward by a light compression spring 106. The forward end of rod 104 is rounded, and is so located as to be received in the topmost one of the cup-like recesses 102. Inasmuch as the recesses are in radial alignment with the cork chambers, it will be evident from inspection of Fig. 4 that the cork magazine is brought to rest in proper registration for the next discharge. When the cork magazine is being stepped from one position to the next, the detent rod 104 is readily moved rearwardly by the camming action between the sloping surfaces of recesses 102 and the rounded end of rod 104.

Attention is now directed to Fig. 5. This shows a toy simulating an automatic pistol. The toy body comprises a barrel portion 110, a handle or grip 112, a trigger or operating lever 114, a cork magazine 116, and an enlarged or oversized muzzle 118 disposed in front of cork magazine 116. The magazine is in this case kept comparatively small in diameter, it being arranged to receive six corks.

The operating mechanism of this gun is shown in Figs. 6, 7 and 8. It comprises a cylinder 120 carrying a rubber gasket 122 at its forward end. A piston 124 is mounted at the forward end of piston rod 126 (made of a flat strip of metal much as previously described), and is normally urged forward by compression spring 128 the rear end of which bears against an appropriate stop 130 extending between the side walls. The trigger 114 is pivotally mounted at 116. The trigger is made of a piece of heavy gauge sheet metal bent to U-shape, as is best shown in Fig. 5. A rod 132 extends between the side walls of the trigger, and is preferably provided with a anti-friction roller 134. This rides against the upper part 136 of an arm 138 the lower end of which is pivoted at 140.

The upper end of arm 138 carries a pawl 142, said pawl being pivotally mounted at 144 and being normally urged upwardly by means of a pull spring 146. The forward end of pawl 142 is formed into a hook 148, said hook being receivable in a slot 150 cut through piston rod 126, as is best shown in Fig. 6. When trigger 114 is drawn rearwardly it moves arm 138 rearwardly, as shown in Fig. 7, and this in turn causes the pawl 142 to pull the piston rod rearwardly to the broken line position 126'. Near the end of the trigger movement, a camming surface 152 on pawl 142 rides against the lower edge of a cross plate and piston rod guide 154, thereby forcing the pawl downwardly and disengaging the hook 148 from the piston rod, thus releasing the piston for abrupt forward movement, all as is indicated in Fig. 7. The trigger is restored by spring 115.

The sealing means for the present gun is much like that previously described. It comprises a strip or link 156, the rear end of which is pivotally connected to trigger 114 at 158. The forward portion of link 156 passes through and is guided by frame wall 160. The end of 75

link 156 carries a depending stud 162 which cooperates with a peripheral rim or ledge 164 on the cork magazine or drum 116. It will be evident that normally, the magazine is free of gasket 122 and of stud 162, as is shown in Fig. 6, but that when the trigger 114 is pulled rearwardly, the stud 162 is drawn rearwardly, and clamps the cork magazine, and particularly the top cork chamber tightly against the gasket 122, as is clearly shown in Fig. 7.

The feed mechanism for the cork magazine is quite different from that previously described. The magazine is fixedly secured to the outer end of a shaft 166 which is rotatably mounted in end plate 168 and a bearing plate 169. The rear end of shaft 166 is provided with a spiral screw. This is most cheaply done, for toy purposes, by simply twisting a strip of metal, as shown at 170, the forward end of twisted strip 170 being secured to the rear end of shaft 166, as is best shown in Fig. 8. A pair of matingly toothed members 172 and 174, forming in effect a unidirectional clutch, are reciprocable on spiral strip 170. The member 172 may be termed a fixed member, it having a pair of outwardly projecting pins or trunnions 176 which are received in links 178. Thus the member 172 is non-rotatable, and it is provided with a hole 180 large enough to clear the spiral strip 170. The other clutch member 174 is provided with a rectangular slit which receives the spiral strip 170. The member 174 is reciprocable along strip 170, but is non-rotatable thereon. The member 174 is normally urged into engagement with member 172 by means of a small compression spring 182 disposed between member 174 and a wall 184 which connects and may be formed integrally with the links 178. The links 178 are pivotally connected to trigger 114 at the point 186.

On reflection, it will be evident that, as trigger 114 is drawn from the position of Fig. 6 to that of Fig. 7, the clutch elements are slid rearwardly on spiral strip 170, during which movement the clutch member 174 is rotated counterclockwise, as viewed from the muzzle of the gun. The clutch teeth are so sloped as to readily permit this movement. When the trigger is released, the clutch assembly is moved forwardly from the position of Fig. 7 to that shown in Fig. 6. At this time the clutch member 174 cannot rotate, it being held against rotation by the clutch member 172. The forward movement of member 174 along spiral strip 170 therefore causes the spiral strip to turn and this is accompanied by rotation of shaft 166 and the cork magazine 116. The pitch of the spiral and the stroke of the clutch therealong are, of course, so relatively proportioned as to produce the desired rotation, which, in the present case, amounts to $\frac{1}{6}$ of a revolution.

The gun is preferably provided with pilot or detent mechanism for proper registration of the cork magazine, and to discourage accidental movement thereof. This detent mechanism as here illustrated is substantially like that previously described, it comprising a detent rod 188 having a rounded forward end and normally urged forwardly by means of a compression spring 190. The detent rod cooperates with a ring of six cone shaped or cup-like recesses indented in the back of the cork magazine, much as was previously described, except that in the present case the recesses may be comparatively shallow and are used solely for pilot or registration purposes, and not for feed purposes.

A modified form of operating mechanism for a toy pistol simulating an automatic gun, is shown in Figs. 9 through 13 of the drawings. Referring to those figures, the air is compressed in a cylinder 192 which is turned inwardly or flanged at its forward end and provided with a rubber gasket 194. A piston 196 is mounted at the forward end of the piston rod 198. This piston rod is a strip of metal, but in the present case is disposed vertically, or edgewise, instead of horizontally. The usual compression drive spring 200 surrounds piston rod 198 and bears at its forward end against the piston and at its rear end against a transverse frame wall 202. The trigger 204 is pivotally mounted on a pin 206. The trigger carries a cam element 208, said element being pivotally mounted between the side walls of the trigger on a pin 210. The cam is normally moved to the position shown in Fig. 9 by means of a spring wire 212. The position of the cam is determined or limited by lugs 214 struck inwardly from the sides of the trigger. The cam element 208 is a U-shaped element providing spaced cams connected by a bottom wall 216. These cams are adapted to ride on opposite sides of the piston rod 198, as is best shown in Fig. 10. As the trigger is pulled rearwardly, the cams 208 bear against studs 218 projecting on opposite sides of the piston rod. The piston rod is thus forced to move rearwardly by the action of cams 208 on studs 218. When the trigger has been pulled nearly to its rearward position, the piston has been retracted and the main spring 200 compressed. The cams 208 are bent outwardly to form escape passages 220. At the end of the trigger stroke the escape passages reach the studs 218, whereupon the piston rod shoots abruptly forward, the studs 218 passing through the escape passage, as is indicated in Fig. 12. When the trigger is restored to initial position (the spring 212 acting also as a restoring spring), the cam element 208 passes around or behind the studs 218, the necessary movement of the cam element being accommodated by pivot 210 and spring 212. When the trigger reaches its full forward position, the spring 212 turns the cam element to the position shown in Fig. 9, thus preparing the same for another operation of the piston.

The feed or stepping mechanism for the cork magazine 222 is much like that last described. The cork magazine is fixedly mounted on the forward end of the shaft 224. The rear end of shaft 224 carries a twisted or spiralled strip 226. A one-way clutch mechanism is slideable on strip 226. The non-rotatable clutch element 228 is provided with sidewardly projecting ears or trunnions 230 (Fig. 13) which are carried in downwardly extending plates 232 (the nearer one is cut away in Fig. 9), said plates being connected to or formed integrally with links 234. These links are connected or joined at their rear ends by a rod 236, which rod passes through a slot 238 in piston rod 198. A similar slot 239 is cut through the piston rod to clear the trigger pivot 206. The links 234 are normally urged forwardly by the upwardly turned ends 240 of a wire spring 242.

With the parts in the normal position shown in Fig. 9, the rod 236 is at the forward end of slot 238. When the trigger is drawn rearwardly, the piston rod 198 is drawn rearwardly, and this in turn pulls the links 234 rearwardly. The links are held in rearward position during discharge of the gun by means of stops 244 formed at the for-

ward part of the cam element. The stops 244 are so located that when the trigger is in rearward position, the stops are ahead of the rod 236, and remain so while the piston rod is released to move forwardly, all as is shown in Fig. 12.

The rotatable part 246 of the unidirectional feed clutch functions exactly like that previously described in connection with Fig. 8, but for toy purposes the part 246 may be stamped out of heavy gauge sheet metal. The result is a six-vaned member best shown in Fig. 13, and provided with a rectangular slot at the center which slidably receives the spiral strip 226. A light compression spring 248 urges the parts of the clutch together. It will be understood that as the trigger is moved rearwardly, the clutch is moved rearwardly, and the rotatable part 246 ratchets backwardly over the non-rotatable part 228. During forward movement of the trigger, the non-rotatable part 228 prevents rotation of the part 246, and the latter turns the spiral member 226 and thereby turns the cork magazine through a desired arc, which in this case is $\frac{1}{6}$ of a revolution.

The detent or locking means for the cork magazine is much like that previously described, it comprising a detent rod 250, the rounded forward end of which is normally urged forwardly by means of spring 252 into engagement with one of a series of six indentations or recesses 254 on the back of the cork magazine.

The sealing mechanism comprises a channel-shaped member 256 the forward part of which is located above the muzzle portion of the gun, and the rearward part of which is located within the gun body, it passing thereto at an opening 258 best shown in Fig. 10. The forward portion of member 256 is guided by a simulated sight 260. It is formed into a hook at 262, said hook being adapted for cooperation with the peripheral rim or ledge 264 of the magazine, as is best shown in Figs. 9 and 11. The rear end of member 256 is provided with detent arms 266 which are spaced apart enough to clear the cams 208. When the links 234 and their cross-rod 236 are moved rearwardly from the position shown in Fig. 9 to the position shown in Fig. 12, the cross-rod 236 bears against the depending arms 266 and forces the sealing member 256 rearwardly, thus causing the hook 262 to clamp the cork magazine tightly against the gasket 194.

Still another form of toy embodying features of the present invention is shown in Figs. 14, 15 and 16. This toy simulates a revolver. It comprises a gun body made of oppositely dished pieces of sheet metal so shaped as to simulate a barrel 270, a cartridge cylinder 272, and a handle or grip 274. The gun is operated by means of an operating lever or trigger 276. A cork magazine 278 is rotatably mounted directly ahead and simultaneously forming a part of the cartridge cylinder 272. The essential change in the present toy is that the operating mechanism has been compacted to very small dimension, thereby bringing the cork magazine 278 rearwardly to its natural position in a revolver. The barrel 270 is, of course, made large enough in diameter to freely clear the corks. Although the operating lever 276 differs in appearance from the trigger of a conventional revolver, this lever is held within and hidden by the hand of a child playing with the toy, and therefore does not detract from the realistic appearance of the toy.

The air compressing mechanism comprises a cylinder 280 having a rubber sealing gasket 282

at its forward end, much as previously described. A piston is movable in cylinder 280 and is connected to the forward end of a piston rod 284. The piston rod is surrounded by a compression spring 286 the forward end of which bears against the piston, and the rear end of which bears against a cross-plate 288, the ends of which are formed into tongues received in the opposite side walls of the gun body.

The gun is provided with a simulated hammer 290. This is pivoted at 292. It is provided with a hook 294 which is hooked into a slot extending transversely of piston rod 284. Rearward movement of the hammer causes rearward movement of the piston rod. The hammer is moved rearwardly by means of a dog 296 carried by a trigger 276. Trigger 276 is a piece of heavy gauge sheet metal bent to U-shape at its lower portion, and providing spaced parallel walls 300 at its upper portion. The trigger is pivoted on a pin 298 extending across the gun body. The dog 296 is pivotally mounted between the side walls 300 by means of lugs or ears 302 (Fig. 16) extending sidewardly from the forward end of plate 296. Plate 296 is also provided with sidewardly projecting ears 304 at its rear end, these ears being somewhat vertically movable in slots 306 (Fig. 15) cut through side walls 300 of the trigger. The dog is normally moved downward by a wire spring 308.

As the trigger 276 is pulled rearwardly, the rear edge of dog 296 bears against the edge 310 of hammer 290, as is best shown in Figs. 15 and 16. The hammer is thus moved rearwardly about pivot 292 and the spring 286 is compressed. Near the end of the trigger movement, a forwardly projecting finger 312 on hammer 290 rises and bears against the dog 296, moving the same upwardly past the surface 310. The hammer is then released for abrupt forward movement with the piston. When the trigger is released, it is moved forwardly by means of a pull spring 314. The dog rides over the surface 316 of hammer 290 and finally, when the trigger has moved all the way forward to the rest position shown in Fig. 15, the spring 308 moves the dog downwardly to its position in front of the hammer surface 310, thus preparing the parts for another operation.

The sealing means will be understood from the drawings, particularly in view of the description of the other guns. It comprises a member 318 having a hook 320 for engaging the periphery of the magazine 278. The member 318 is provided with sidewardly spaced arms 322, said arms being pivotally connected to trigger 276 at the point 324. As the trigger is moved rearwardly, the hook 320 is moved rearwardly, and clamps the cork magazine into tight engagement with the gasket 282 at the forward end of the air compressing cylinder.

The feed or stepping mechanism for the cork magazine probably requires no detailed description, it being much like that described in connection with the simulated sub-machine gun of Figs. 1 through 4. It employs a pawl rather than a spiral or screw element with a unidirectional clutch. Specifically, there is a pawl 326 which is pivoted at 328, and is provided with a depending arm 330 connected at 332 to the forward end of a link 334 which is itself connected to trigger 276 by means of a pin 336. The connection preferably includes a slot 338 for lost motion. The mounting of the pawl on pin 328 also preferably includes a slot 340 to afford retraction of the pawl during its passage from one

recess to the next, it being understood that the back of the cork magazine is provided with a ring of six recesses corresponding to the six cork chambers of the magazine. The pawl is normally moved to the position shown in Fig. 15 by means of a restoring and feed spring 342.

As the trigger is pulled rearwardly, the pin 336 moves in slot 338. Toward the end of the trigger movement when the lost motion has been used up, the link 334 is moved toward the left, as shown in Fig. 15, thereby moving the pawl downwardly. The pawl rides out of the recess 346, this being facilitated by slot 340, and moves downwardly to the next lower recess. As the trigger moves forwardly, the restoring spring 342 moves the pawl inwardly and upwardly, thereby feeding the cork magazine ahead to bring another cork into position in front of the air compression cylinder.

The cork magazine is properly located by means of a detent 348 which functions just as was previously described, and in cooperation with the lowermost one of the recesses.

The forms of the invention so far described have employed rotatable cork magazines. It is possible, however, to also use a cork magazine of the flexible or link type. Thus, referring to Figs. 17 and 18, the cork magazine is made up of a series of links 350, each shaped to form a cork receiving chamber 352. These chambers are loaded with corks 354, and the link magazine is passed through appropriate windows 355 in the side walls of the gun body 358 which in the present case, simulates a sub-machine gun. Only the forward end of the gun is shown. It will be understood that appropriate guides 356 forming a part of the gun mechanism insure a properly guided horizontal travel of the links as they pass in front of the air cylinder. It will also be understood that sealing means almost exactly like that previously described may be used to draw the uppermost link against the rubber gasket at the forward end of the air cylinder at the time of firing of the gun. The feed mechanism may be much like that previously described, but modified to operate at the uppermost link of the magazine (instead of at the side or bottom of a rotatable magazine). In a sense, the chain-like cork magazine may be considered to be a large cork wheel only the upper peripheral portion of which is passing through the gun mechanism.

Moreover, it is not essential for the cork magazine to be flexible. A simple straight, rigid strip may be used. Thus, referring to Fig. 19, the cork magazine comprises a strip 360 carrying a series of cork chambers 362. These may be secured to the strip 360 by flanging or riveting the same in place as is shown at 364 in Fig. 20. The strip may be provided with a series of holes 366, said holes functioning for cooperation with a suitable feed pawl which steps the strip ahead from one cork chamber to the next. The strip may, of course, be drawn into tight sealing engagement with the forward end of the air cylinder by sealing means exactly like that previously described.

This idea will be clear from inspection of Fig. 21. The air cylinder 368 is like that previously described. The strip 360 is guided by the stationary guide 370 and a movable guide 372, the latter being formed at the end of a sealing member 374 similar to those previously described. The feed pawl 376 feeds strip 360, the pawl being actuated by mechanism much like that already described.

It is believed that the construction and operation, as well as the many advantages of our improved cork shooting toy, will be apparent from the foregoing detailed description thereof. The toy is provided with a cork magazine having a series of cork receiving chambers. The magazine is preliminarily loaded with corks by simply pressing the same into the cork chambers. When the magazine is a rotatable magazine, it is readily rotated to facilitate the insertion of corks provided, of course, that it is turned in its direction of free movement. To operate the gun, it is then merely necessary to pull the operating lever or trigger. All of the mechanism is preferably though not necessarily operated by a single lever. In such case, the lever, during its rearward movement, compresses the piston spring and seals the cork magazine tightly against the air cylinder. Near the end of the trigger stroke, the piston is released for abrupt forward movement, but the magazine is held sealed against the air cylinder. The cork is forcibly ejected with a percussive noise, much as in the case of an ordinary pop gun. As the trigger is released, the sealing engagement between the magazine and the air cylinder is released, and the feed mechanism steps the cork magazine ahead to bring another cork in front of the air cylinder.

In the claims, we have, for brevity and convenience, used the term "cork," but this is to be understood as including rubber or other equivalent suitable material, as well as cork. Moreover, the projectile need not be frustoconical in shape. It may, for example, be spherical, and of somewhat oversize diameter so as to fit snugly in the magazine chambers. We intend the claims to include such a variation in shape.

It will be understood that the mechanisms may be housed in various types of toy bodies to simulate other weapons than those illustrated. It will also be understood that mechanisms of known type may be used in which the piston spring is compressed and the gun cocked by separate mechanism independent of the trigger, and a separate trigger may then be used for the sole purpose of releasing the piston and firing the gun. It will therefore be apparent that while we have shown and described our invention in preferred forms, many changes and modifications may be made in the structures disclosed, without departing from the spirit of the invention defined in the following claims.

We claim:

1. A toy comprising a cylinder, a piston movable in said cylinder, a cork magazine movably mounted in communication with said cylinder and having a series of individual cork-receiving chambers, a gasket at the magazine end communicating with the cylinder, intermittently operable means for pulling the magazine against the gasket to form a sealed connection therebetween, and means for actuating said piston in the cylinder in order to eject the cork from the chamber then held in communication with the cylinder.

2. A toy comprising a cylinder, a piston movable in said cylinder, a cork magazine movably mounted at one end of said cylinder and having a series of individual cork-receiving chambers, a gasket at the end of the cylinder, intermittently operable means for pulling the magazine against the gasket to form a sealed connection therebetween, intermittently operable means for stepping the magazine ahead to the next cork chamber when the sealing means is released, and

means for actuating said piston in the cylinder in order to eject the cork then held in front of the cylinder by the magazine.

3. A toy weapon comprising a cylinder, a piston movable in said cylinder, a cork magazine rotatably mounted at one end of said cylinder and having a series of individual cork-receiving chambers, a gasket at the end of the cylinder, intermittently operable means for pulling the magazine against the gasket to form a sealed connection therebetween, intermittently operable means for rotating the magazine ahead to the next cork chamber when the sealing means is released, and means for actuating said piston in the cylinder in order to eject the cork then held in front of the cylinder by the magazine.

4. A repeating cork shooter comprising an air compressing cylinder, a piston movable in said cylinder, a piston rod, a spring, means for retracting the piston rod and piston and compressing the spring, a movable magazine for carrying a plurality of corks, said magazine being so mounted that the cork chambers are moved successively into alignment with and disposed in front of the air cylinder, a gasket at the end of the cylinder, sealing means for pulling the magazine against the gasket, and additional means for stepping the magazine to the next cork to be discharged.

5. A repeating cork shooter comprising an air compressing cylinder, a piston movable in said cylinder, a piston rod, a spring, means for retracting the piston rod and piston and compressing the spring, a rotatable magazine for carrying a plurality of corks, said magazine being so mounted that one of the cork chambers is in alignment with and disposed in front of the air cylinder, a gasket at the end of the cylinder, sealing means for pulling the magazine against the gasket, and additional means for rotating the magazine to the next cork to be discharged.

6. A repeating cork shooter comprising an air compressing cylinder, a piston movable in said cylinder, a piston rod, a spring, a lever for retracting the piston rod and piston and compressing the spring and thereafter releasing the piston rod for abrupt forward movement of the piston, a rotatable magazine for carrying a plurality of corks, said magazine being so mounted that one of the cork chambers is in alignment with and disposed in front of the air cylinder, a gasket at the end of the cylinder, sealing means actuated by said lever for pulling the magazine against the gasket during operation of the lever, and additional means actuated during movement of the lever for rotating the magazine to the next cork to be discharged.

7. A repeating cork gun comprising a gun body having a simulated barrel, a grip, a trigger, an air compressing cylinder in said gun body, a piston movable in said cylinder, a piston rod, a spring, means for retracting the piston rod and piston and compressing the spring, and a movable magazine for carrying a plurality of corks, said magazine being so mounted that one of the cork chambers is in alignment with and disposed in front of the air cylinder.

8. A repeating cork gun comprising a gun body having a simulated barrel, a grip, a trigger, an air compressing cylinder in said gun body, a piston movable in said cylinder, a piston rod, a spring, means actuated by said trigger for retracting the piston rod and piston and compressing the spring and thereafter releasing the piston rod for abrupt forward movement of the piston, and a movable magazine for carrying a

plurality of corks, said magazine being so mounted that the cork chambers may be moved successively into alignment with the air cylinder.

9. A repeating cork gun comprising a gun body having a simulated barrel, a grip, a trigger, an air compressing cylinder in said gun body, a piston movable in said cylinder, a piston rod, a spring, means actuated by said trigger for retracting the piston rod and piston and compressing the spring and thereafter releasing the piston rod for abrupt forward movement of the piston, and a rotatable magazine for carrying a plurality of corks, said magazine being so mounted that one of the cork chambers is in alignment with and disposed in front of the air cylinder.

10. A repeating cork gun comprising a gun body having a simulated barrel, a grip, a trigger, an air compressing cylinder in said gun body, a piston movable in said cylinder, a piston rod, a spring, means actuated by said trigger for retracting the piston rod and piston and compressing the spring and thereafter releasing the piston rod for abrupt forward movement of the piston, a movable magazine for carrying a plurality of corks, said magazine being so mounted that one of the cork chambers is in alignment with and disposed in front of the air cylinder, a gasket at the end of the cylinder, and sealing means actuated by said trigger for pulling the magazine against the gasket during firing of the gun.

11. A repeating cork gun comprising a gun body having a simulated barrel, a grip, a trigger, an air compressing cylinder in said gun body, a piston movable in said cylinder, a piston rod, a spring, means actuated by said trigger for retracting the piston rod and piston and compressing the spring and thereafter releasing the piston rod for abrupt forward movement of the piston, a movable magazine for carrying a plurality of corks, said magazine being so mounted that one of the cork chambers is in alignment with and disposed in front of the air cylinder, and additional means actuated during the restoring movement of the trigger for stepping the magazine to the next cork to be discharged by the gun.

12. A repeating cork gun comprising a gun body having a simulated barrel, a grip, a trigger, an air compressing cylinder in said gun body, a piston movable in said cylinder, a piston rod, a spring, means for retracting the piston rod and piston and compressing the spring, a rotatable magazine for carrying a plurality of corks, said magazine being so mounted that one of the cork chambers is in alignment with and disposed in front of the air cylinder, a gasket at the end of the cylinder, sealing means for pulling the magazine against the gasket during firing of the gun, and additional means for rotating the magazine to the next cork to be discharged by the gun.

13. A repeating cork gun comprising a gun body having a simulated barrel, a grip, a trigger, an air compressing cylinder in said gun body, a piston movable in said cylinder, a piston rod, a spring, means actuated by said trigger for retracting the piston rod and piston and compressing the spring and thereafter releasing the piston rod for abrupt forward movement of the piston, a rotatable magazine for carrying a plurality of corks, said magazine being so mounted that one of the cork chambers is in alignment with and disposed in front of the air cylinder, a gasket at the end of the cylinder, sealing means actuated by said trigger for pulling the magazine against

the gasket during firing of the gun, and additional means actuated during the restoring movement of the trigger for rotating the magazine to the next cork to be discharged by the gun.

14. A repeating cork shooter comprising air compressing means, a rotatable magazine for carrying a plurality of corks successively into communication with the air compressing means, and additional means for rotating the magazine to the next cork to be discharged, said means including a spiral strip connected to the magazine, a non-rotatable ratchet wheel slidable along said strip and connected to an operating lever for movement thereby, and a mating ratchet wheel slidable along said strip but rotatable therewith, the ratchet teeth being so faced that they disengage during pulling of the lever in one direction but engage during opposite movement of the lever in order to rotate the magazine.

15. A repeating cork shooter comprising an air compressing cylinder, a piston movable in said cylinder, a piston rod, a spring, a lever for retracting the piston rod and piston and compressing the spring and thereafter releasing the piston rod for abrupt forward movement of the piston, a rotatable magazine for carrying a plurality of corks successively in alignment with the air cylinder, and additional means actuated during restoring movement of the lever for rotating the magazine to the next cork to be discharged, said means including a spiral strip connected to the magazine, a non-rotatable ratchet wheel slidable along said strip and connected to the lever for movement thereby, and a mating ratchet wheel slidable along said strip but rotatable therewith, the ratchet teeth being so faced that they disengage during pulling of the lever but engage during return of the lever, in order to rotate the magazine.

16. A repeating cork gun comprising a gun body having a simulated barrel, a grip, a trigger, an air compressing cylinder in the gun body, a piston movable in said cylinder, a piston rod, a spring, means actuated by said trigger for retracting the piston rod and piston and compressing the spring and thereafter releasing the piston rod for abrupt forward movement of the piston, a rotatable magazine for carrying a plurality of corks successively in alignment with the air cylinder, a gasket at the end of the cylinder, sealing means actuated by the trigger for pulling the magazine against the gasket during firing of the gun, and additional means actuated during restoring movement of the trigger for rotating the magazine to the next cork to be discharged, said means including a spiral strip connected to the magazine, a non-rotatable ratchet wheel slidable along said strip and connected to the trigger for movement thereby, and a mating ratchet wheel slidable along said strip but rotatable therewith, the ratchet teeth being so faced that they disengage during pulling of the trigger but engage during return of the trigger, in order to rotate the magazine.

17. A toy comprising air-compressing means, a cork magazine movably mounted for communication therewith and having a series of individual cork-receiving chambers, each of said chambers being adapted to receive an ordinary tapered cork with the large end of the cork projecting out of the forward face of the chamber, means whereby the chambers loaded with corks may be brought successively into communication with the air-compressing means without interference by the projecting ends of the corks, and means bearing

against a part of the magazine rearwardly of the forward face of the magazine and so constructed and arranged as to hold the rear end of a loaded chamber tightly against the forward end of the air-compressing means.

18. A toy gun comprising a simulated gun barrel, air-compressing means, a cork magazine movably mounted behind said barrel for communication with said air-compressing means and having a series of individual cork-receiving chambers, each of said chambers being adapted to receive an ordinary tapered cork with the large end of the cork projecting out of the forward end of

the chamber, the front of the magazine being spaced from the rear end of the barrel to provide a clearance for the projecting ends of the corks, means whereby the chambers loaded with corks may be brought successively into communication with the air-compressing means, and means to hold the rear end of a chamber tightly against the forward end of the air-compressing means without obstructing the path of movement of the cork out of the forward end of the chamber.
